ATTORNEY'S

Patented June 8, 1926.

UNITED STATES PATENT OFFICE.

PLEASANT AUGUSTUS MAY, OF DALLAS, TEXAS.

FUEL TANK.

Application filed February 20, 1925. Serial No. 10,691.

This invention relates to fuel tanks and has for its object the provision of a device for conserving a definite quantity of fuel when the fuel gets low in a tank and is 5 adapted to serve as a warning to motorists that the quantity of fuel in the tank is limited.

A further object of the invention is the provision of a device adapted to be connected to the usual sediment bulb of a fuel tank and inserted within the fuel tank for maintaining a limited quantity of fuel in the tank after the fuel has reached a certain level, with a further provision for releasing 15 the reserved fuel at the will of the operator of an automobile.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claim.

In the drawings:—

Figure 1 is a transverse vertical section 30 of the fuel tank showing my invention applied thereto.

Figure 2 is a view in perspective and partly in section of the device for providing for an emergency fuel supply with the parts 35 of the same shown in separated relation.

Figure 3 is a vertical section of the fuel controlling device in normal position.

Figure 4 is a view in elevation showing a modified form of my invention.

Figure 5 is a side elevation of the tank partly broken away and in section showing the application of my invention.

Referring more particularly to the drawings, 1 designates a fuel tank having a countersunk, threaded opening 2 into which is screwed a filling cap 3. The filling cap is provided with an opening 4 through which is movable a chain or cable 5. A spring clip 6 is mounted on the cap 3 and is adapted to secure the upper end of the cable in any position desired. An enlargement 7 prevents the same from passing through the perforation 4.

The bottom of the tank is reinforced as 55 shown by a nipple 8 which is provided with an internally threaded opening adapted to

receive the threaded nipple 9 of a sediment bulb 10. The passage of liquid fuel from the tank 1 through the sediment bulb as is usual is controlled by a turning plug valve 60 11 and a feed line 12 connected with the bulb for supplying fuel to the usual carburetor.

The diameter of the nipple 9 of the bulb 10 is sufficient to permit the bore or usual passage 13 to be machined and threaded to receive the reduced threaded end 14 of a valve cage 15. The valve cage for a portion of its length is cut away to form elongated lateral passages 16 through which the fuel in the tank is adapted to flow at a predetermined rate and when the cylindrical valve 17 is lifted through the cable 5. The cage 15 is of such a diameter that it may be readily inserted through the usual threaded bore in the nipple 8 at the bottom of the fuel tank. The valve 17 is hollow and cylindrical in shape and has its upper and lower ends open, the cable 5 being connected thereto by means of a handle 18 to the upper end 70 of the valve 17.

A coiled spring 19 is housed in the cage and engages at its lower end the upper end of the valve 17 being adapted to maintain the valve upon its seat 20 in the cage 15 its upper end engaging the bushing nut 21. 80 The upper end of the cage 15 is internally threaded as shown at 22 to receive the threads on the bushing nut 21. The nut 21 is provided with a flared bore 23 through which the fuel in the tank is adapted to normally flow and through which the cable 5 is adapted to freely move for operating the valve 17. It will be appreciated that the fuel also passes through the openings 16 to the cage 15 and enters the open upper end 90 of the valve 17.

In Figure 4 is shown a slightly modified form of the invention and in which the nipple 9^a of the sediment bulb 10 is screwed into an internally and externally threaded bushing 24. The bushing is screwed into the usual openings 8^a of the threaded openings in the reinforcement 8 and the tank 1 and the lower threaded end 14 of the valve cage 15 is screwed into the internally threaded 100 upper end of the bushing 24. The remaining elements of the construction are similar in every respect to the construction shown in Figure 1. It will be seen that in each case it will be unnecessary to machine the 110 nipple 9^a of the sediment bowl to receive the reduced threaded end 14 of the valve

cage 15 since such threaded end of the valve cage is screwed into the bushing 24.

In the operation of either of the devices shown in Figures 1 or 4 the cylindrical valve 17 is normally maintained upon its seat 20 in the cage 15 by the coil spring 19 and the chain or cable 5 has its upper free end beyond the cap closure 3 held in position by the spring clip 6. The gasoline will normally pass through the flared bore 23 and also through the passages 16 and through the valve 17 through bore 13 into the sediment bulb 10 filling the same and through the feed line 12 to the carbureter. As the gasoline or fuel drops to the level which is in the same plane with the top of the cylindrical valve 17 flow of gasoline will cease from the bulb 10 and cause the engine to stop. The operator of the car is thus warned that 20 a reserve of approximately a gallon of gasoline still remains in the tank and that by drawing on the cable 5 and maintaining the valve 17 in an elevated position this reserve of fuel in the tank may then be fed to the carbureter. Such a warning will be sufficient to cause the operator of the car to make haste to the nearest gasoline station for additional fuel.

The lower reduced threaded end 14 of the 30 valve cage has a central passage 25 therethrough whereby the tank 1 is maintained normally in open communication with the sediment bowl 10.

It will be seen from an inspection of the 35 figures that the valve may be operated by a chain in a vertical line or by a chain disposed at an angle, when the closure cap for the

gasoline tank is located to one side of the sediment bulb, and the flaring of the bore of nut 21 facilitates the operation and prevents 40 sticking or jamming of the valve, or chain 5.

What I claim is:—

In a fuel tank, means for maintaining a predetermined quantity of fuel in the tank, comprising a sediment bulb having a cylindrical valve cage, removably connected to the sediment bulb at its upper end, said cage being of less diameter than said end of the sediment bulb, and adapted to be connected with the fuel tank, said cage having elongated lateral openings, said tank being provided with a threaded opening, said sediment bulb having threads adapted to be screwed into the threaded opening, a hollow cylindrical valve slidably mounted in said cage and adapted to close said elongated lateral openings to a predetermined height or level, said cage having its upper end internally threaded, a bushing nut held within the said upper end of the cage, said nut having a central bore flared upwardly, a chain connected at one end with said valve, and passing through the flared bore, the other end of said chain adapted to be passed through an opening in the top of said tank located to 60 one side of the vertical plane of the cage, a coiled spring housed in the cage between the valve and the bushing nut, for maintaining the valve upon its seat, the length of the valve determining the level and quantity of reserve fuel retained in the tank after 65 the fuel has been normally drawn off.

PLEASANT AUGUSTUS MAY.
